(57) **CLAIM**

The ornamental design for a pipe coupling, as shown and described.

DESCRIPTION

FIG. 1 is a perspective view showing a pipe coupling in accordance with a first embodiment of my new design; FIG. 2 is a front elevational view of the first embodiment; FIG. 3 is a rear elevational view of the first embodiment; FIG. 4 is a right side elevational view of the first embodiment;

FIG. 5 is a left side elevational view of the first embodiment; FIG. 6 is a top plan view of the first embodiment; FIG. 7 is a bottom plan view of the first embodiment; FIG. 8 is a perspective view showing a pipe coupling in accordance with a second embodiment of my new design; FIG. 9 is a front elevational view of the second embodiment; FIG. 10 is a rear elevational view of the second embodiment; FIG. 11 is a right side elevational view of the second embodiment;

FIG. 12 is a left side elevational view of the second embodiment;

FIG. 13 is a top plan view of the second embodiment; and, FIG. 14 is a bottom plan view of the second embodiment. The solid gray surface shading represents a contrast in appearance. The broken lines shown in the drawings depict portions of the pipe coupling that form no part of the claim.

1 Claim, 10 Drawing Sheets
